(57) **CLAIM**

The ornamental design for an integral gutter and fascia board, as shown and described.

DESCRIPTION

FIG. 1 is a top, left-hand end, front isometric-type view of an integral gutter and fascia board with a central portion of indeterminate length removed, showing a first embodiment of our new design (the appearance of the removed central portion is identical in all respects to the appearance of the portions of the length that are shown);

FIG. 2 is a left-hand end elevation view thereof, the right-hand end elevation being a mirror image;

FIG. 3 is a front elevation view thereof;

FIG. 4 is a rear elevation view thereof;

FIG. 5 is a top plan view thereof;

FIG. 6 is a bottom view thereof;

FIG. 7 is a top, left-hand end, front isometric-type view of an integral gutter and fascia board with a central portion of indeterminate length removed, showing a second embodiment of our new design (the appearance of the removed central portion is identical in all respects to the appearance of the portions of the length that are shown);

FIG. 8 is a left-hand end elevation view thereof, the right-hand end elevation being a mirror image;

FIG. 9 is a front elevation view thereof;

FIG. 10 is a rear elevation view thereof;

FIG. 11 is a top plan view thereof; and,

FIG. 12 is a bottom view thereof.
